BONE CONDUCTION UNIT

Hugh S. Knowles, River Forest, Ill., assignor to
 Zenith Radio Corporation, a corporation of
 Illinois

Application October 27, 1944, Serial No. 560,667

2 Claims. (Cl. 179—107)

1

The present invention relates to hearing aid receivers or earphones of the "bone conduction" type having a vibratile element arranged to transmit vibrations to the auditory nerve through the bony structure of the head of a user.

It is well known that excessive force between a bone conduction unit and the wearer's bony structure causes discomfort and even injury to the wearer. It is therefore desirable to provide a bone conduction unit which is arranged to give the wearer thereof some indication, if and when, excessive force exists between the unit and the wearer's bony structure. This feature is desirable, because when one first places the bone conduction unit in position, it is difficult to determine whether too much force is being exerted. Such excessive force in prior art arrangements usually is felt only after a long period of continuous wear, and by that time the discomforts and annoyances of excessive pressure in the form of headaches, impaired blood circulation, reddening of the skin, etc., are sending their warnings.

The term excessive force is used throughout the present specification but it is understood the excessive force existing between the casing and the wearer's bony structure causes excessive unit pressure to exist. In practice the unit pressure is different at different contact regions and is equal to the component of the force normal to the person's skin divided by the area in the particular region considered, it being apparent that this unit pressure at such regions depends, inter alia, upon the shape of the mastoid bone when the bone conduction unit is mounted above the mastoid bone.

Because of the limited electrical output of hearing aid amplifiers due to space and weight requirements, etc., it is highly desirable to efficiently convert such electrical output into vibratory energy and then efficiently transfer such vibratory energy to the auditory nerves of the user. Users of bone conduction units quickly find usually by trial and error that converted sounds are louder when the pressure of bone conduction unit on the head of its user is increased. Users of the prior art devices, of the type which are pressed against the user's head by the usual resilient supporting headband, oftentimes purposely or otherwise adjust the headband by distorting, bending, etc., it so as to cause relatively high pressures to exist for one or more of the following purposes: of producing enhanced loudness, of producing different tone quality, or of producing a condition whereby the unit is less apt to "crawl" or "slide" on the user's head.

High pressures produced for these purposes or in many cases resulting inherently from the initial store or factory adjustment are tolerated until the tissue and skin become hypersensitive as they

do when such high pressure is continued. Headaches commonly result from the continued application of high pressure and in many cases actual deformity of the adjacent bony structure occurs. As a result the common practice is to periodically move the bone conduction unit relative to the head, to remove it completely for extended periods, or to adjust the headband by bending, distorting, etc. it after the above described discomforts are observed. If the user is preoccupied he may not introduce such change in operating conditions until the discomfort is relatively acute and after such discomfort has persisted for many hours. Consequently, common practice in the wearing of bone conduction units appears to be that the user initially is subjected to high pressures over and above those necessary for satisfactory transmission of sound and later in order to minimize discomfort it is necessary for the user to reduce such pressure below a magnitude satisfactory for good transmission of sound.

The recognition of these unpleasant effects resulting from sustained high pressure on the user's bony structure and the possibility of serious complications resulting from these effects is so widespread among otologists that many of them recommend a bone conduction unit only when an air conduction unit gives very unsatisfactory results.

On the other hand, if inadequate pressure exists between the bone conduction unit and user's bony structure transmission is impaired, the intensity of vibration induced in the user's body structure is reduced and furthermore the amount of sound transmission as a function of frequency is altered. Consequently, the overall response-frequency characteristic is impaired and must be altered for optimum tone quality, and in addition the user has lost some sense of loudness. The reduced loudness causes the user to increase the amplifier gain and to frequently overload the amplifier with the result that a high annoyance factor resulting from impairment in the quality of music and from impairment in quality and articulation of speech results.

It follows then that from an acoustical viewpoint, depending upon the meaning ascribed to the term desirable pressure, there are two types of desirable pressure, i. e. (1) a high pressure for excellent sound transmission from the bone conduction unit to the wearer's bony structure but too high in pressure for sustained operation because of the resulting undesirable physiological effects produced in the individual and (2) a pressure sufficiently high for good sound transmission from the bone conduction unit to the wearer's bony structure but low enough so as not to cause the resulting undesirable physiological effects in

the user. It is this second type of desirable pressure which applicant produces with the apparatus described herein together with means for warning the user when and if pressures greater than this second type of desirable pressure exists whereby the user may be protected against harm of a physiological nature. Subjectively, this second type of desirable pressure varies with different individuals and in bone conduction units arranged to rest above the mastoid bone and the pressure is within a pressure range resulting from the application of a force of 6 to 20 ounces to a contact face having an area substantially equal to .8 square inch.

Inasmuch as the desirable pressure range varies with different individuals it is desirable for the purposes of the present invention that the bone conduction unit itself may be adjusted by the user to provide a warning when more than desirable pressure of the second type is exerted. Or, the unit itself may for example be adjusted at the factory, on a statistical basis, to provide a warning when the pressure exceeds either the pressure corresponding to an application force of 20 ounces or an average pressure between the range corresponding to an application of 6 to 20 ounces in a so-called hypothetical normal person.

A third type of desirable pressure may be mentioned. Such third type of desirable pressure is present when the bone conduction unit is mounted poorly for good sound transmission from the unit to the user's bony structure but is mounted to rest with great comfort on the user's person. This condition of operation results in the disadvantages mentioned previously. It will be readily seen that applicant's mode of operation of the bone conduction unit for realizing the second type of desired pressure corresponds to an adjustment intermediate the adjustments for obtaining the first and third types of operation mentioned above.

There has existed for a long time the need for a headband supported bone conduction unit which would automatically warn the user when this second type of operation was not present. As will be set forth presently this condition is realized by the user when the bone conduction unit satisfactorily engages the head with sufficient high pressure for suitable sound transmission and perhaps tone but with sufficiently low pressure so as not to cause loss of sound from the unit. This want has particularly been present in bone conduction arrangements which are supported other than by the user's hand and by means which exert a substantially constant continuous force over a relatively long period of time such as headbands or other types of harness. Although the bone conduction arrangement including the bone conduction vibratile member and headband may be set so that the user need not determine at a later time the pressure which is excessive, excessive pressure may later be developed after the arrangement is displaced from its initially adjusted position through normal or abnormal activities of the user. Such excessive pressure may be produced through inadvertent or careless bending or adjustment of the headband, or from wearing a hat placed too tightly on the headband while the instrument is being worn.

It is therefore an object of the present invention to provide a bone conduction unit which is arranged to give the wearer thereof some indication when and if excessive force exists between the unit and the wearer's bony structure.

A further object of the present invention is to

provide an improved bone conduction arrangement which provides an adjusted warning point of pressure which should not be exceeded.

Still another object of the present invention is to provide an improved bone conduction arrangement which warns the wearer instantly, by loss of sound, whenever force of the arrangement against the wearer's bony structure exceeds an amount likely to cause excessive discomfort after continued use.

Yet another object of the present invention is to provide an improved bone conduction arrangement which causes the vibratile member thereof to be inoperative for the efficient transmission of acoustical energy when pressure is higher than that for which the arrangement is adjusted.

It is also an object of the present invention to provide an improved earphone of the bone conduction type having a casing which is arranged to move with respect to a relatively stationary supported magnet assembly, the driving motor being especially arranged so that excessive pressure of the casing against the head of a user during sound reception causes loss of movement of the casing.

It is further desirable that, when once a warning has been given to the wearer in response to excessive pressure between the unit and the wearer's bony structure, such warning be discontinued after the pressure is again adjusted to a lower normal operating pressure without manipulating elements in the unit such as by shaking the unit, etc.

It is therefore a further object of the present invention to provide an improved bone conduction arrangement which becomes inoperative when excessive pressure exists on the wearer's bony structure and which is immediately restored to operativeness when and if the excessive pressure is removed.

The features of the present invention which are believed to be novel are set forth with particularity in the appended claims. The present invention itself, both as to its organization and manner of operation, together with further objects and advantages thereof may best be understood by reference to the following description taken in connection with the accompanying drawings in which:

Figure 1 shows certain elements of apparatus embodying the present invention;

Fig. 2 shows an arrangement mounted in operative position on a person and utilizing a principle of the present invention;

Fig. 3 shows an exploded view of part of the apparatus shown in Fig. 1;

Fig. 4 shows an assembled view of apparatus shown in Fig. 1;

Figs. 5 and 6 are sectional views taken respectively on lines 5—5 and 6—6 of Fig. 4;

Fig. 7 shows parts of a modified structure embodying the present invention;

Fig. 8 is a sectional view taken along line 8—8 of Fig. 7;

Fig. 9 is a sectional view taken along line 9—9 of Fig. 7;

Fig. 10 is a sectional view of a portion of Fig. 7;

Fig. 11 is a perspective view of the apparatus of Figs. 1 and 2 arranged on a person for the transfer of vibratory energy.

Figs. 12—14 show a modified arrangement for adjusting the device of Fig. 1, Figs. 12 and 13 being sectional views respectively taken substantially on the same lines as is Figs. 5 and 6 and

Fig. 14 being an elevational view of the arrangement; and

Fig. 15 shows certain characteristics of apparatus embodying the present invention.

The particular bone conduction arrangement shown in Figs. 1-6 and 11 is of the type adjusted on a statistical basis so as to allow a so-called normal person to obtain the second type of operation mentioned above with the assurance that he will be automatically warned when operation is of the first and third types also mentioned previously.

The modified arrangement shown in Figs. 12-14 is of the type which any particular user may adjust without taking the bone conduction unit apart whereby the unit may be adjusted accurately to his own particular needs to obtain the second type of operation mentioned above with the assurance that he will be automatically warned when operation is of the first and third types.

In Fig. 1 the bone conduction earphone or receiver designated generally by the numeral 10 and embodying a principle of the present invention, comprises a casing 11, a magnet assembly 12 and a movable armature 13 arranged to be fixed to cover 14 of casing 11, a magnet assembly support bar 15 arranged to be fixed on magnet assembly 12 by nut 16 (Fig. 3) and arranged also to screw threadedly receive a pair of yoke supporting pins 17, 18 which extend respectively through a pair of oppositely disposed slightly oversized openings 19 and 20 in casing 11, the openings 19 and 20 being made oversized to allow vibratory movement of casing 11 relative to the pins 17 and 18.

As illustrated in Figs. 2 and 11, the casing 11 is arranged to press against a suitable portion of the user's head, for example, the mastoid bone, by mounting the composite earphone, or receiver 10, on a suitable headband 21 having a resilient yoke member 22 which partially surrounds casing 11 (Fig. 4) and resiliently and frictionally engages the enlarged body portions of pins 17 and 18 on an axis corresponding to line 6-6 in Fig. 4, the yoke member 22 having a pair of oppositely disposed apertures 23 and 24 and being frictionally mounted on one leg of L-shaped member 25 by means of rivet 26. The other end of L-shaped member 25 is frictionally mounted on one end of headband 21 by means of rivet 27. The casing 11 is thus mounted, for adjustment relative to a person's mastoid bone, not only for rotative movement about the axis of pins 17 and 18 but also for rotative movement about the axis of rivet 26 and for rotative movement about the axis of rivet 27.

The casing cover 14 arranged to contact a region on the wearer's skin near the wearer's mastoid bone is made concave along its longitudinal axis only as shown in comparison in Figs. 7 to 9 and is pressed into suitable contact with a region near the wearer's mastoid bone by forces resulting from the stressed resilient headband 21, which forces are transmitted through the frictional connections previously described and bearing the reference numerals 28, 29, 30 and 31. This particular shape of the contact surface of cover 14 and frictional connections 28, 29, 30 and 31 allows the cover 14 to satisfactorily engage the wearer's head and reduces the tendency of casing cover 14 to "crawl" off the mastoid bone and further controls the low frequency response by giving more uniform compliance between the user's head and casing 11. This term, compli-

ance, is used in its generally accepted meaning in the acoustical engineering art as set forth in the book "Applied Acoustics," by Olson and Massa (2nd edition published by P. Blakiston's Son & Co., Inc., Philadelphia, 1939).

With this arrangement, the force exerted by the casing 11 on the user's head is dependent upon the resiliency of band 21 or forces exerted on such band, for example, by the wearer's hat.

Another feature of the particular headband construction shown in Figs. 2, 4, and 11 is that a receiver, or earphone 10, of the bone conduction type is held in operative position with the headband extending over the top of the user's head so that the user's normal activities influence in a relatively small degree the force of casing 11 containing magnet assembly 12 on a suitable portion of his head.

The magnet assembly 12, including the armature 13 is shown in an exploded view in Fig. 3, and in sectional views in Figs. 5 and 6.

In Fig. 3, the armature 13 of magnet assembly 12 is disposed within, and formed integrally with, a surrounding flexible member 32 having a pair of oppositely disposed ears 33 and 34, the armature 13 being joined to the surrounding portion 32 by portions 69 and 61 of predetermined resiliency. The armature 13 is fastened to the casing cover 14 by means of a pair of countersunkhead screws 35 and 36 (see Fig. 4) passing through casing cover 14 and engaging the tapped cylindrical studs 37 and 38 mounted on armature 13 the casing cover 14 in turn being fastened to casing 11 by means of countersunkhead screws 62, 63 and 64 (Fig. 4).

The armature 13 and the integrally formed surrounding member 32 are supported on the magnet assembly 12 by means of a pair of screws 39 and 40 (Fig. 6) passing respectively through apertures 41 and 42 in ears 33 and 34, the screws being threadedly held in ears 43 and 44 of top plate 45 of the magnet assembly 12. Spacers or shims 46 and 47, interposed respectively between ears 33 and 43 and between ears 34 and 44, hold the movable armature 13 in predetermined spaced relationship to core member 48. The thickness of these shims are of importance, as will be seen later, in determining the force necessary between casing 11 and the wearer's mastoid bone to cause armature 13 to be inoperative for transmitting intelligence.

The strap or bar 15 is fastened by nut 16 to the bottom of base plate 50 of magnet assembly 12. Bar 15 has a pair of ears 51 and 52 each having a tapped hole therein for engagement with threaded pins 17 and 18 (Figure 1) arranged to project through openings 19 and 20 in casing 11.

These previously described parts of magnet assembly 12 are mounted on the base plate 50. In addition, magnet coil 54 is fixedly mounted on base 50 by passing the reduced threaded portion 56 of core member 48 through the insulating annular coil form 65 having mounted thereon the magnet coil 54, and threading nut 16 on threaded portion 56 so as to clamp bar 15 between base plate 50 and nut 16.

Permanent magnet pole pieces 57 and 58 (Figs. 3 and 5), preferably of the type having aluminum as one of its constituents, are clamped in spaced relationship between base plate 50 and top plate 45 by means of a pair of countersunkhead screws 59 and 60 passing respectively through apertures 61 and 62 in the base plate 50, through clearance openings 63 and 64 in magnets 57 and 58 and screw threadedly engaging top plate 45 in tapped holes 66 and 67, the coil form 65 being

also clamped between base plate 50 and top plate 45.

It is thus seen that the armature 13 joined to the resilient surrounding member 32 by integral resilient portions 60 and 61 (Fig. 3) is mounted in spaced relationship to core 48 and that magnetic flux of sufficient intensity in core 48 may cause movement of armature 13, such movement being opposed by the resilient nature of portions 60, 61 and surrounding member 32.

In a practical physical embodiment, the movable armature 13 is formed of suitably bonded plates of suitably enlarged cross sectional area for the flow of magnetic flux from coil 54 or magnets 57 and 58 through a return magnetic part and has mounted thereon the spaced tapped cylindrical portions 37 and 39 for fastening casing cover 14 to movable armature 13 whereby casing 11 follows the movement of armature 13.

One of the important features of the present invention is that the armature 13 is arranged to transmit suitable low intensity vibrations to the casing 11 without the production of any "locking" or "freezing" action or without the distortion of audible sounds resulting from such vibrations when normal forces are exerted between casing 11 and the wearer's mastoid bone but does produce cessation or diminution of movement of movable armature with respect to its field structure when and if slightly more than normal forces are exerted between the casing 11 and the wearer's mastoid bone. In other words, even though the armature 13 may touch the core member 48 in the inoperative position of armature 13, the tension forces developed in connecting members 60, 61 and surrounding members 32 increase more than proportionally with their displacement with the net result that the restoring forces developed are always greater than the magnetic forces existing between core member 48 and armature 13 and hence no "locking" or "freezing" of the armature 13 results. For this purpose, member 32 and integrally formed members 60 and 61 (Fig. 3) connecting the armature 13 to its ring shaped flexible supporting member 32 made of such dimensions and of such material that normal forces exerted between the user's head and casing 11 cause a relatively small amount of movement of armature 13. But, the portions 60 and 61 and ring shaped member 32 are sufficiently flexible so that armature 13 and casing 11 produce sound vibrations without distortion when currents of sound frequency and of suitable intensity flow through coil 54 from terminals similar to terminal 68 in Fig. 5 which terminals have a projecting contact 69 arranged to make contact with an electrical plug type contact frictionally held in opening 70 in casing 11.

When currents of voice frequency flow from a pair of contacts, similar to contact 68 in Fig. 5, and through coil 54, magnetic flux is set up in coil 54. A first portion of such flux traverses core member 48, armature 13, top plate 45, magnet 57, bottom plate 50, and returns to core member 48. A second portion of such flux traverses core member 48, armature 13, top plate 45, magnet 58, bottom plate 50, and returns to core member 48. Both of these first and second mentioned courses of the flux are effective jointly to cause movement of armature 13 and casing 11 in response to current flow through coil 54. The magnets 57 and 58, of course, are poled such that they produce a magnetic field in core member 48 substantially equal to twice that produced by one magnet alone.

In the preferred embodiment of the present invention, the air gap distance between armature 13 and pole piece 48 is of the order of .003 inch to .005 inch when no force exists between casing 11 and the wearer's mastoid bone. This air gap distance is of such amount and the resiliency of ring shaped member 32 and connecting portions 60 and 61 are such that when forces above a predetermined magnitude are present between casing 11 and the wearer's mastoid bone the armature 13 is displaced from operating position and is ineffective to transmit variations produced by currents of voice frequency flowing in coil 54. When the abnormal force which produces such abnormal displacement of the armature is removed, the armature is automatically effective to resume its normal operation of vibrating in accordance with currents of voice frequency in coil 54. In other words, so long as the armature 13 transmits vibrations to the wearer's mastoid bone, the wearer is automatically advised that normal forces exist between casing 11 and his mastoid bone but, when such force exceeds a predetermined safe force, the wearer is automatically informed by loss of sound that such force is excessive. Excessive force between the casing 11 and the wearer's mastoid bone oftentimes results from the wearer's hat worn so as to produce relatively large stress in the headband 21 which contacts the wearer's hat. In such case, oftentimes, the resilient headband 21 is depressed into the space bearing the reference numeral 72 in Fig. 2 and accordingly, the casing 11 is pressed too hard against the wearer's mastoid bone. When such condition exists the wearer is automatically informed by loss of sound that such condition exists.

The particular manner of mounting the armature 13 with the resilient portions 60 and 61 (Fig. 3) symmetrical about the line 6—6 in Fig. 4 allows the bone conduction unit proper to be used effectively even though the unit may be inadvertently or carelessly mounted in position on the user's head without excess force existing between casing 11 and the wearer's mastoid bone. Moreover, such portions 60, 61 and ring 32 are of such size and shape so as to bend at small amplitudes of vibration of armature 13 and to be predominantly tensioned when armature 13 tends to vibrate with increasing amplitude. Thus, the manner of mounting armature 13 with the symmetrically and integrally formed resilient portions 60, 61 and 32 not only assures operation when the bone conduction unit proper is slightly improperly positioned without the introduction of excessive pressure but also assures conversion of electrical energy into vibratory energy of low amplitude, and also assures stopping the vibration of the armature 13 when excessive forces are introduced between the casing 11 and the wearer's mastoid bone.

Furthermore, cessation of vibration of the armature 13 is prevented in use, when normal forces exist between the casing 11 and wearer's mastoid bone, not only by causing proportionally larger tension forces to appear in resilient portions 60, 61 and 32 when armature 13 is displaced objectionably large distances from its static position, but also due to the fact that increased eddy currents flowing in the unlaminated armature 13 cause a greater demagnetization of the field from core 48 as armature 13 approaches core 48. Also since the magnetic circuit is of such cross sectional area for the flow of magnetic flux that saturation and consequent reduction

of permeability results when the armature 13 tends to move too close to core 48.

In the normal range of movement of armature 13 within a restricted low amplitude range, the armature 13 is displaced a distance linearly proportional to the intensity of current flowing through winding 54. This is accomplished in some degree by suspending the armature 13 by means of the resilient members 60, 61 and 32 such that proportionally larger tension forces arising in such members oppose the proportionally larger magnetic forces on armature 13 as it approaches core member 48. That is, the increasing positive stiffness of the composite armature 13 as it moves toward the core 48 is substantially offset by complementary, negative resistance arising from increasing attraction between the armature 13 and core 48.

In Fig. 7 the magnet assembly 12 is mounted on the cover 14 in the manner described above but the assembly 12 is connected to a headband through a universal connection 74 shown in greater detail in Fig. 10. One part 75 of the universal joint is rigidly connected to the field structure of assembly 12 by means of a screw threaded connection and extends through a clearance opening 76 in the back of a modified casing 77, the cover 14 being secured on casing 77 by means of screws disposed in tapped holes 78 in casing 77. The other part 79 of the universal joint may be connected to a headband.

In the various arrangements shown herein the casing 11 or 77 is made to vibrate with respect to the armature assembly 12 and for that reason oversized holes 19, 20 and 76 are made in the casing so as to allow freedom of movement. In order to prevent foreign materials entering the unit and impeding the movement of armature 13 or assembly 12 with respect to casing 11 resilient washers such as shown in Fig. 13, resiliently engaging members 17, 18 may be employed to form a closure member for the openings 19, 20.

Figs. 12-14 show a modified arrangement incorporating means for adjusting the bone conduction unit to the particular needs of an individual in a manner so that the individual may be warned of the existence of an adjustable predetermined force existing between casing 11 and his bony structure. That is, means are provided for adjusting the unit to different predetermined forces at which the unit becomes inoperative. Corresponding parts in the various figures herein are allocated identical reference numerals and the additional structure in Figs. 12-14 is described now.

The tension on armature 13 is adjusted by compressing leaf spring 80 by adjusting the position of adjusting screw 81 held screw threadedly in rigid yoke member 82 which extends around the magnet assembly and abuts armature 13. It is apparent that it is in the scope of one skilled in the art to permanently fasten the yoke member 82 to armature 13 by conventional means, if desired. Leaf spring 80 having its ends abutting base plate 50 and its recessed center portion engaged by the end of adjusting screw 81 is guided during its adjustment and held in its adjusted position by means of pins 83, 84 which extend through cooperating apertures in the spring 80. It is readily apparent that the spring 80 is disposed between the relatively stationary magnetic field structure and its cooperating armature 13 and when compressed causes the armature 13 to move closer to the core member 48. Further-

more, the greater the compression of leaf spring 80, the lesser the force between casing 11 and the wearer's mastoid bone need be to cause armature 13 to be inoperative to transmit vibratory energy to the individual's mastoid bone.

The position of adjusting screw 81 determines the force necessary to cause armature 13 to be inoperative and may be suitably indicated on casing 11 by providing suitable cooperating scale 85 on casing 11 and indicia 86 on screw 81. The designation "H" on casing 11 in Fig. 14 signifying that part of scale 85 which corresponds to high forces necessary to cause armature 13 to be inoperative for the transmission of vibratory energy and conversely, that part of the scale bearing the designation "L" corresponds to low forces necessary to cause armature 13 to be inoperative for the transmission of vibratory energy. The region marked "H" may correspond to a force of 20 ounces and the region marked "L" may correspond to 6 ounces with each scale graduation corresponding to a force of two ounces.

Fig. 15 shows the response-frequency variation of vibratory energy transferred subjectively to an individual when as in curve 87 the bone conduction unit is suitably mounted for obtaining the second type of desired operation mentioned above wherein the casing 11 is pressed against the individual's anatomy with a force sufficient for good sound transmission and good tone quality and not too excessive to produce inoperativeness of armature 13; and, when as in curve 88 the bone conduction unit is mounted for obtaining the so-called third type of operation mentioned above wherein casing 11 is pressed against the individual's anatomy with a force much less than that necessary to cause inoperativeness of armature 13 and for great comfort.

It is readily apparent from the shapes of curves 87 and 88 when drawn into comparison, that the third type of operation mentioned above is automatically realized by the individual who may provide the necessary adjustment by bending the attached headband 21 etc. in order to obtain enhanced loudness and enhanced overall tone quality.

While particular embodiments of the present invention have been shown and described, it will be obvious to those skilled in the art that changes and modifications may be made without departing from this invention in its broader aspects, and, therefore, the aim in the appended claims is to cover all such changes and modifications as fall within the true spirit and scope of this invention.

55 I claim:

1. A bone conduction unit including a driving structure and a casing surrounding said driving structure, said driving structure including a magnetic field structure, a pole piece supported in said field structure and an armature supported on said magnetic field structure in normally spaced relationship to said pole piece to permit vibration of said armature in response to those variations in density of magnetic flux from said pole piece corresponding to audio signal currents impressed on said field structure, said armature being connected to a first region on said casing to transmit vibrations to said casing, a spring element interposed between a second region on said casing and on the side of said field structure opposite said armature and positioned to exert a force on said field structure in the direction of said armature, and an adjusting element associated with said spring to vary the force exerted on said field structure.

2. A hearing aid of the bone conduction type which requires a pressure contact with a user's anatomy to induce the sensation of hearing efficiently, said hearing aid including a driving structure and a casing surrounding said driving structure, said driving structure including a magnetic field structure, a pole piece supported in said field structure and an armature supported on said magnetic field structure in normally spaced relationship to said pole piece to permit vibration of said armature in response to those variations in density of magnetic flux from said pole piece corresponding to audio signal currents impressed on said field structure, said armature being connected to a first region on said casing to transmit vibrations to said casing, a spring element interposed between a second region on said casing and on the side of said field structure opposite side armature and positioned to exert a force on said field structure in the direction of said armature tending to effect a condition of inoperability of said driving structure, means for holding said hearing aid in forceful contact with the user's anatomy, said means being mechanically coupled to said field structure through one or more apertures in said casing to cause such

5 10 15 20 25

holding force to be exerted on said field structure in aiding relationship to the spring force whereby said field structure is urged in forceful contact with said armature to cause a condition of inoperativeness when the combination of the spring and holding forces is excessive, and an adjusting element associated with said spring to vary the force exerted on said field structure whereby inoperability may be adjusted to occur at a predetermined excessive holding pressure.

HUGH S. KNOWLES.
